Primary Examiner — Ramzi S Almatrahi(74) *Attorney, Agent, or Firm* — Young Basile Hanlon & MacFarlane, P.C.(57) **CLAIM**

The ornamental design for a camera housing, as shown and described.

DESCRIPTION

FIG. 1 is a front, top, and right side perspective view of a camera housing showing our new design;
FIG. 2 is a front, bottom, and left side perspective view thereof;

FIG. 3 is a back, top, and left side perspective view thereof;
FIG. 4 is a back, bottom, and right side perspective view thereof;

FIG. 5 is a front elevational view thereof;

FIG. 6 is a back elevational view thereof;

FIG. 7 is a left side elevational view thereof;

FIG. 8 is a right side elevational view thereof;

FIG. 9 is a top plan view thereof; and,

FIG. 10 is a bottom plan view thereof.

The broken lines in the drawings showing portions of the camera housing form no part of the claimed design.

1 Claim, 9 Drawing Sheets---
